CLAIM

The ornamental design for a UHF RFID tag, as shown and described.

DESCRIPTION

FIG. 1 is an enlarged rear top right perspective view of a UHF RFID tag showing our new design;

FIG. 2 is an enlarged front top right perspective view thereof;

FIG. 3 is an enlarged front elevational view thereof;

FIG. 4 is an enlarged rear elevational view thereof;

FIG. 5 is an enlarged top plan view thereof;

FIG. 6 is an enlarged bottom plan view thereof;

FIG. 7 is an enlarged left side elevational view thereof; a right side elevational view is a mirror image thereof;

FIG. 8 is the rear top right perspective view of FIG. 1;

FIG. 9 is the front top right perspective view of FIG. 2;

FIG. 10 is the left side elevational view of FIG. 3; and,

FIG. 11 is a front top left perspective thereof.

The broken line showing of an attachment strip in FIGS. 8-11 is included for the purpose of illustrating the UHF RFID tag in a configuration of use and forms no part of the claimed design.
